UNITED STATES PATENT OFFICE.

JOHN G. DIXON, OF NEW YORK, N. Y., ASSIGNOR TO HERMANN WILCK, OF SAME PLACE.

COLLAR OR CUFF DRYING MACHINE.

SPECIFICATION forming part of Letters Patent No. 495,244, dated April 11, 1893.

Application filed February 28, 1891. Serial No. 383,278. (No model.)

To all whom it may concern:

Be it known that I, JOHN G. DIXON, a citizen of the United States, residing in the city, county, and State of New York, have invented 5 certain new and useful Improvements in Collar or Cuff Drying Machines, of which the following is a specification.

This invention has reference to certain improvements in the patent for collar and cuff drying machines for which Letters Patent were granted to me, No. 431,766, dated July 8, 1890, which improvements are designed with the view of simplifying the construction of the apparatus and of rendering the same more 15 effective while in use, especially as regards the shutting out of the cold air from the drying chamber, the arrangement of the curved tracks for the movable carrier-frames, and the arrangement of the driving sprocket 20 wheels in a separate compartment, said compartment being made movable and adapted to be arranged relatively to the drying chamber so that the endless chain by which the carrier-frames are moved can be tightened 25 from time to time as required.

The invention consists substantially as hereinafter shown and described of an improved collar and cuff drying machine which is composed of a drying chamber having horizontally arranged steam-coils, and movable valves at the out-going end. Endless drive-chains are mounted on guide sprocket-wheels and are moved by rotary sprocket-wheels of larger size which are arranged in a separate 30 compartment which is capable of adjustment toward the drying chamber so as to keep the endless drive-chains taut. To the endless chains are pivoted a number of carrier-frames on which the screens containing the collars 35 and cuffs are placed. At the out-going end of the drying chamber an auxiliary endless chain is arranged carrying pendent valves that are so arranged as to drop into the space between two carriers, said valves preventing 40 the ingress of the cold air into the drying chamber.

The invention consists further of certain additional details of construction, which will be fully explained hereinafter and finally 45 pointed out in the claims.

In the accompanying drawings, Figure 1

represents a vertical longitudinal section of my improved collar and cuff drying machine, showing the drying chamber with its vestibule at the ingoing end and the pendent 55 valves at the outgoing end, also the adjustable compartment containing the driving sprocket-wheels. Fig. 2 is a top-view of a modified form of carrier-frame, showing its connection with the drive-chains and the 60 tracks on which it is moved. Fig. 3 is a perspective view of a portion of the drying chamber, with the casing broken away so as to show the relative position of the tracks, steam-pipes, sprocket-wheels, drive-chains 65 and carrier-frames.

Similar letters of reference indicates corresponding parts.

Referring to the drawings, A represents the drying chamber which is supported on cross-timbers made in the shape of a rectangular box or compartment the walls of which are made of wood and lined with sheet metal. The drying chamber A is provided with inlet openings a at the bottom, for the admission 70 of cold air, and with outlet openings a' at the top part for the escape of the hot air and the moisture evaporated from the articles passed through the drying chamber. In the drying chamber A are arranged a number of horizontal steam-coils B, the lowermost coil of which is arranged close to the bottom of the drying chamber and extended from one end to some distance from the opposite end, while the remaining coils are arranged at proper intervals one above the other. The coils B extend alternately from opposite ends of the drying chamber but terminate at some distance from the opposite end-wall, so as to leave 75 a sufficient space for permitting the passage 80 of the carrier-frames alternately around said steam-coils in their passage through the drying chamber. Above and close to the steam-coils B are arranged horizontal tracks C C which are preferably supported on brackets 85 b attached to the side-walls of the drying chamber A. On the tracks C C are guided a number of carrier-frames D which are moved over the tracks in close proximity to the steam-coils so as to receive the full effect of the radiant heat of the steam-pipes. The carrier-frames D are supported on rollers or wheels 90 95 100

applied to diagonally opposite corners of the same, said carrier-frames being pivoted by laterally-extending center pivots d' to the drive-chains E which are guided over sprocket-wheels E' that are arranged alternately at opposite ends of the drying chamber but intermediately between the steam-coils arranged in the same, as shown clearly in Fig. 1. The shafts of the sprocket-wheels E' are supported in suitable journal bearings of the side-walls of the drying chamber A , said sprocket-wheels serving simply as guide-wheels for the drive-chains, while two sprocket-wheels E^2 of larger diameter than the sprocket-wheels E' serve as driving wheels for the endless chains E . The larger driving sprocket-wheels E^2 are located in an independent compartment F which is supported by anti-friction rollers on longitudinal supporting timbers attached to the floor. The auxiliary compartment F is, like the drying chamber, made of wood lined with sheet metal and contains the driving sprocket-wheels. The driving sprocket-wheels E^2 extend through an opening in the top-part of the compartment F so that the drive-chains can pass from the same to the vestibule A' at the in-going end of the drying chamber, as shown in Fig. 1. The shaft of the sprocket-wheels E^2 is supported in bearings of the compartment F and receives rotary motion by suitable transmission from a power-shaft, while all the movable parts of the apparatus receive their motion from the shaft of the sprocket-wheels E^2 . Setting screws f pass through the end-wall of the compartment F next adjoining the wall of the drying chamber A and press against said end-wall, said screws serving to adjust the relative position of the movable compartment F to the drying chamber A and permit thereby the taking up of the slack of the drive-chains in case of the stretching or lengthening of the same by use. The drive-chains form, in connection with the carrier-frames pivoted thereto, a so-called endless sectional apron which is continually kept in motion so as to pass the articles placed on the same through the drying chamber and subject them during their passage, to the drying action of the heat in the same.

The carrier-frames D are made of oblong shape and adapted to support the screens on which the articles to be dried are placed. The carrier-frames D are provided with wheels or rollers d that are placed on short axles located at diagonally opposite corners of the same, said rollers or tram-wheels being designed to support the weight of the carrier-frames which are placed on the drive-chains while moving over the horizontal parts of the tracks and to maintain the carrier-frames in a horizontal position while the drive chains are moving over the sprocket-wheels at the curved portions of the tracks. The roller d at one corner of the carrier-frame D is guided along the track attached to one side-wall of the drying chamber, while the roller d at the diagonally

opposite corner of the carrier-frame is guided along the track supported on the opposite side-wall of the drying chamber. When drying heavy and bulky articles on the carrier-frames they may be arranged with rollers d at each corner, in which case two tracks are arranged at each side of the drying chamber for the rollers as shown in Fig. 2. At the points where the carrier-frames pass around the sprocket-wheels, the guide-tracks are curved and extended over and parallel with the horizontal track portions next below the same, as shown in Fig. 1, the inner curved portions of the track being provided with gaps or recesses b^x for the passage of the pivots connecting the frames D with the drive-chains. By means of the curved end-portions of the tracks C the carrier-frames D are readily transferred from the upper tracks to the intermediate and lowermost tracks in the drying chamber. By the curved end portions of the tracks certain defects in the arrangement of the tracks described in my prior patent were overcome, inasmuch as it enables the rollers of the carrier-frames to leave the end of one track and pass along the overlapping extensions of the curved end portions and the curved portions until the carrier-frames have rounded the sprocket-wheels and arrived at the next horizontal track portion. While rounding the supporting sprocket-wheels E' the weight of the carrier-frames is entirely upon the pivots of the drive-chains which are supported at that time by the sprocket-wheels E' . It will be observed that no gaps are required in the curved portions of the tracks for those rollers which are at that time either at the front or rear of the carrier-frames, whereby a steady and easy motion of the frames around the sprocket-wheels is obtained. The gaps are only sufficiently large to permit the passage of the connecting pivots or trunnions of the carrier-frames and chain, but not large enough to allow the guide-rollers to pass through the same, so that the latter are compelled to move along the tracks and produce thereby the steady, horizontal motion of the carrier-frames through the drying chamber. The curved end portions of the tracks are like the horizontal portions supported by brackets extending from and attached to the side-walls of the drying chamber. The forward end of each carrier-frame D is provided with an upwardly extending flange d^x which is nearly equal in width with the height of the narrow vestibule A' arranged at the in-going end of the drying chamber A . This vestibule is formed of parallel walls which form a throat-like extension of the drying chamber above the compartment F . The vestibule is of somewhat greater length than the width of a carrier-frame, so that the flanges on passing into the same partially close the vestibule, by which the ingress of a good deal of cold air which would seriously injure the ventilation in the drying chamber is prevented. The flanges d^x are preferably made of sheet iron and pro-

vided with flexible edges of canvas or other suitable material so as to make a perfect joint when passing through the vestibule A'.

At the outgoing end of the drying chamber

- 5 A where the drive-chains with their carrier-frames make their exit from the same, it is impracticable to use a vestibule in the same manner as at the ingoing end of the drying chamber, for the reason that in drying collars 10 or cuffs or like articles they are liable to curl up or increase otherwise in bulk and size so as to be liable to be scraped off from the carrier-frames when passing through the narrow exit opening. To prevent, however, the entrance of cold air at the outgoing end, movable valves g are arranged which are applied to an endless chain g' that is supported on sprocket-wheels g^2 and arranged between horizontal partitions g^3 at some distance from 15 the bottom of the drying chamber. These horizontal partitions g^3 are attached to the side-walls of the drying chamber and form two passages, the upper for the return-motion of the valves and the lower for the carrier-frames. The sprocket-wheels g^2 are driven by suitable transmission from the sprocket-wheel E' next above the outgoing end of the drying chamber as shown in Fig. 1. The valves g are pivoted to the endless chain g' 20 and are so arranged as to drop in the space between two adjoining carrier-frames. The chains g' are propelled at the same rate of speed as the drive-chains to which the carrier-frames are pivoted, so that the pendent 25 doors or valves g travel with the same speed and keep thereby the outgoing passage at the rear of each carrier-frame closed. The endless chain g' is prevented by horizontal rails g^4 from sagging by the weight of the pendent 30 valves. While the valves move through the lower passage, their upper ends will be close to the lower horizontal partition g^3 , while their lower ends will drag upon the floor of the 35 drying chamber. As each of these valves emerges from the drying chamber, it will be lifted by the endless chain g' around the sprocket-wheels and passed in inclined position through the narrow upper passage between the partitions g^3 until they are dropped 40 again into the space between the carrier-frames, the valves keeping thereby the outgoing air passages closed while allowing the carrier-frames to pass from the drying chamber A into the adjoining compartment F. 45 When drying more bulky substances, it may be desirable to use movable valves operated by an endless chain at the ingoing end of the drying chamber in the same manner as at the outgoing end.
- 50 60 The operation of the apparatus is similar to the one described in my prior patent before referred to, with this difference that the

screens are placed on the sectional apron at the upper part of the driving sprocket-wheels E' near the vestibule at the ingoing end of the drying chamber. The articles that are to be dried are then conducted through the drying chamber and dried by the heat produced in the same by the steam-coils, the moisture evaporated being carried off by the upward draft established between the bottom and top-ventilating openings of the drying chamber. When the carrier-frames leave the drying chamber the articles on the same are conducted to the box of the compartment F, where they are taken off from the carrier-frames by the attendants, and subjected to the ironing operation.

Having thus described my invention, I claim as new and desire to secure by Letters Patent—

1. The combination, with a drying chamber having guide-tracks provided with curved portions at alternately opposite ends, of guiding sprocket-wheels at the curved portions, a separate movable compartment for receiving the articles when dried, driving sprocket-wheels of larger diameter in said compartment, endless drive-chains over the guiding and driving sprocket-wheels, and means for adjusting the separate compartment relatively to the drying chamber so as to keep the drive-chains taut, substantially as set forth.

2. The combination, of a drying chamber, horizontal heating coils in the same, tracks having curved end portions at alternately opposite ends, endless drive-chains, guiding sprocket-wheels for said chains located in the drying chamber, driving sprocket-wheels outside of the same, an auxiliary endless chain at the outgoing end of the drying chamber and pendent valves applied to said chain and adapted to close the outgoing end of the drying chamber, so as to prevent the ingress of the cold air, substantially as set forth.

3. The combination, with a drying chamber, of endless drive-chains, carrier-frames pivoted thereto, horizontal partitions at the outgoing end of a drying chamber, an endless chain moving at the same speed as the drive-chains and valves pivoted to said auxiliary chain, said valves dropping between the carrier-frames and being adapted to close the outgoing end of the drying chamber and prevent the ingress of the cold air, substantially as set forth.

In testimony that I claim the foregoing as my invention I have signed my name in presence of two subscribing witnesses.

JOHN G. DIXON.
